DESIGN FOR A BOTTLE OPENER

Ferdinand R. Gioscio, Indianapolis, Ind.

Application June 10, 1933. Serial No. 48,365

Term of patent 7 years

To all whom it may concern:

Be it known that I, FERDINAND R. GIOSCIO, a citizen of the United States, residing at No. 131 North Noble Street, Indianapolis, in the county of Marion and State of Indiana, have invented a new, original, and ornamental Design for a Bottle Opener, of which the following is a specification, reference being had to the accompanying drawing, forming part thereof.

The figure is a side elevation of a bottle opener showing my new design, the same being substantially flat and of negligible thickness.

I claim:

The ornamental design for a bottle opener, substantially as shown and described.

FERDINAND R. GIOSCIO.
